UNITED STATES PATENT OFFICE.

MAURICE L. POWERS AND JOSHUA W. MAYER, OF NEW YORK, N. Y.

DESIGN FOR A FINGER-RING.

SPECIFICATION forming part of Design No. 24,195, dated April 16, 1895.

Application filed March 22, 1895. Serial No. 542,867. Term of patent 3½ years.

To all whom it may concern:

Be it known that we, MAURICE L. POWERS and JOSHUA W. MAYER, citizens of the United States, and residents of New York, in the county of New York and State of New York, have invented a certain new and useful Design for a Finger-Ring, of which the following is a specification, reference being had to the accompanying drawing, which

10 shows a perspective view of a finger-ring embodying our design.

The leading feature of our design consists in the representation upon each side of the setting of a finger ring, the crown or equivalent of the setting, of an elk's head, *a*, *a*, the horns or antlers of which, *b*, *b*, form the prongs of the setting. The ring, adjacent to the

head is chased, embossed or otherwise treated, as at *c*, *c*, to give the semblance of the hair on the elk's neck.

As above stated, the space between the horns or antlers of the elk is decorated in any suitable manner, as shown.

We claim—

15 The design for a finger ring herein shown and described.

Signed at New York, in the county of New York and State of New York, this 16th day of March, A. D. 1895.

MAURICE L. POWERS.
JOSHUA W. MAYER.
